UNITED STATES PATENT OFFICE.

OLOF ALBIN NORD, OF VAVENBY, BRITISH COLUMBIA, CANADA.

TRAP.

Application filed February 2, 1925. Serial No. 6,431.

To all whom it may concern:

Be it known that I, OLOF ALBIN NORD, a subject of the King of Great Britain, and a resident of the town of Vavenby, in the 5 Province of British Columbia, Canada, have invented certain new and useful Improvements in Traps, of which the following is a specification.

My invention relates to improvements in 10 traps, with more particular reference to devices for trapping fur-bearing animals, and the object of my invention is to provide a device of this character which is of the simplest construction, inexpensive to manufacture and saleable at a low cost, and which is highly practical and efficient, operating without the use of springs or teeth so that risk of injury to the fur of the animal is eliminated while at the same time it is 15 possessed of strong and positive gripping properties.

I attain this object by the construction illustrated in the accompanying drawings in which—

25 Fig. 1 is a face view of the trap, set.
Fig. 2 is a face view of the trap, sprung.
Fig. 3 is a side view of the trap.
Fig. 4 is a fragmentary view, showing the trip device.

30 Fig. 5 is a view illustrating the manner in which the trap is used.

Similar figures of reference indicate similar parts throughout the several views.

1 indicates a piece of strong spring steel 35 wire of suitable size formed into a double ring continuous throughout its length of suitable diameter having divided ends, one ring coil 2 being in front of the rear ring coil 3 which is of somewhat smaller diameter than the front one, and the divided ends 4 and 5 of the ring are arranged at the bottom of the same and substantially opposite one another, as shown in Fig. 2. The rings 2 and 3 are spaced apart so as to permit

40 of the insertion movably therebetween of a single ring 6 of approximately the same diameter as the clear opening through the double ring, and this single ring is capable of being placed in registration with the double ring opening, indicated by the numeral 7, as shown in Fig. 1, or of moving right to the top of the opening 7, as shown in Fig. 2, being prevented from disengagement from the double ring when at the top 45 of the same by a clamp 8 which spaces the ring coils 2 and 3 apart while at the same

time securing them against spreading, this clamp being inside the movable ring 6 when the device is assembled together. The ring 6 is set inwardly as at 9 a short distance 50 down on one side, as shown in Figs. 1 and 2, and this inset part underlies, when the trap is set, a second clamp 10 secured to the rings 2 and 3 acting also as a spacer for the rings similar to clamp 8, this arrangement providing for a sidewise movement of the ring 6 at the commencement of its movement across the opening 7 when tripped. At its top centre the ring 6 is provided with 55 a swivel connection 11 to which is secured a strong wire 12 of suitable size and length.

13 indicates a U-shaped bracket having its leg 14 longer than the opposite leg 15 and to the leg 14 near its upper end are secured 60 the divided ends 4 and 5 of the ring coils 2 and 3 while through both legs 14 and 15 passes the circular portion 16 of the double ring so that the bracket is thus rigidly secured to the double ring. Pivotedly connected at its lower end on the portion 16 which lies between the legs 14 and 15 of the U-shaped bracket is a hook shaped member 17 the length of which is such that its hooked upper and free end 18 engages 65 without slackness the single ring 6 when the trap is set, while pivotally connected at one end to the said upper and free end 18 of the member 17 is an arm or lever 19 the opposite end of which is formed as an open frame 20 the upper edge of which is provided with upstanding sharp pointed projections 21. The end of the arm 19 remote from the frame end is cut out, as at 22, to bear on the ring 6 against the side thereof when set so as to prevent it from dropping 70 until the trap is sprung.

23 indicates a swivel eye connected to the bottom of the U-shaped bracket 13 to which eye is freely connected a spike 24. 75 The manner in which the trap is used and operates may be briefly described. A suitable tree, indicated by the numeral 25, is selected, one in which a branch 26 may be used, and a selected log is also taken, 27 in Fig. 5 out of which at a suitable point a chip is cut so as to leave a substantially vertical face 28 at the rear end of the chipped out part. The spike 24 is then driven into the face 28 and the wire 12 is secured to the branch 26 so that the log is positioned below the same and at an upward inclination 80 when the trap is set, the inner and lower

100

105

110

end of the log abutting the tree trunk, as indicated in Fig. 5. The trap is set by moving the ring 6 down to register with the double ring opening 7 and hooking the 5 hooked upper end of the trip member 17 on the bottom end of the ring 6, the arm 19 and frame 20 being then horizontal and on the far side of the rings remote from the tree, and forcing a strip of wood or bark 10 29 on to the points 21 so as to lie transversely of the rings. From this it will be seen that when the trap is ready and set for trapping the log 27 is supported at an inclination by means of the wire 12 and spike 24, the weight of the log being on 15 the double ring which, however, is prevented from dropping through the engagement of the trip member 17 on the ring 6. The bait, 30, is placed on the log beyond 20 the trap so that in order to reach it the animal must pass through the rings and in attempting to do so places the feet on the bark strip fastened to the frame 20, tripping by its weight the hook 17, whereupon 25 the log 27 drops, carrying the double ring with it so that the animal is caught between the upper side of the double ring and the lower side of the single ring 6 and securely held since the whole weight of the log is on 30 it, and being suspended without the possibility of obtaining a foothold or purchase has no chance of freeing itself and escaping, nor of damaging the fur through its 35 struggles. It should be noted that, in addition to the vertical closing movement of the rings, the provision of the inset portion 9 ensures a simultaneous sidewise movement to the ring 6 on the commencement of its movement out of registration with the 40 double ring due to the engaging of the inset portion with the clamp 10 which forces the ring 6 laterally so that the ring opening 7 is contracted rapidly, not only vertically but horizontally, and thus a very quick gripping 45 action is ensured.

From the foregoing it will be seen that I have devised a simple and inexpensive trap which is highly practical and efficient.

What I claim as my invention is:

50 1. A trap comprising a double ring the coils of which are spaced apart, a single ring provided at its upper end with a swivel and a wire attached to the swivel freely connected to said double ring and movable 55 across the opening of the same, a U-shaped bracket secured to the bottom of the double ring provided with a swivel and a spike

freely connected to said swivel, a link pivoted at one end to the double ring between the legs of the said bracket having its upper end adapted to bear in trip-fashion on the bottom end of the single ring when the latter is placed in registration with the double one, and an arm pivoted at its inner end to the said link adapted under pressure on its outer end when horizontal to trip the link clear of the single ring. 60 65

2. A trap comprising a double ring the coils of which are spaced apart, a single ring provided at its upper end with a swivel and a wire attached to the swivel freely connected to said double ring and movable across the opening of the same, a U-shaped bracket secured to the bottom of the double ring provided with a swivel and a spike 70 75 freely connected to said swivel, a link pivoted at one end to the double ring between the legs of the said bracket having its upper end adapted to bear trip-fashion on the bottom of the single ring when the latter is placed in registration with the double one, and an arm pivoted at its inner end to the said link adapted under pressure on its outer end when horizontal to trip the link clear of the single ring, the outer end 80 85 of said arm being provided with upstanding sharpened projections. 90

3. A trap comprising a double ring the coils of which are spaced apart by an upper and a side clamp, a single ring freely connected by the upper clamp to said double ring between the coils thereof and movable across the opening of the same, said ring having an inset portion underlying the side clamp when in registration with the double ring whereby a sidewise movement is imparted to it on the commencement of its movement out of registration with the double ring, trip means carried by the double ring 95 for holding the single ring in registration therewith, a spike carried by the double ring adapted to attach the same to a load, and a wire connected to the single ring adapted to suspend it from a stationary support. 100

4. A trap comprising a pair of connected rings one movable across the opening of the other, trip means for holding the two rings in registration, and means for imparting sidewise movement to one ring on the commencement of its movement out of registration with the other. 105 110

Dated at Vancouver, B. C., this 21st day of January, 1925.

OLOF ALBIN NORD.
